Primary Examiner — Dana Meyrow(74) *Attorney, Agent, or Firm* — Knobbe, Martens, Olson & Bear, LLP**CLAIM**

The ornamental design for a bottle, as shown and described.

DESCRIPTION

FIG. 1 is a front view of a bottle of our design, the rear view being the same;

FIG. 2 is a right-side view of the bottle of FIG. 1, the left-side view being the same;

FIG. 3 is a top view of the bottle of FIG. 1; and,

FIG. 4 is a bottom view of the bottle of FIG. 1.

All features in broken line form no part of the claimed subject matter.

1 Claim, 4 Drawing Sheets(56)
